CLAIM

The ornamental design for a computer screen with graphical user interface simulating a layout, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 : Front view of a computer screen with graphical user interface simulating a layout according to a first embodiment; and,

FIG. 2 : Front view of a second embodiment thereof. The outer edge of the underlying computer screen is understood to be congruent with the graphical user interface.
